(57) **CLAIM**

We claim the ornamental design for a semiautonomous weapon mount, substantially as shown and described.

DESCRIPTION

This invention was made with Government support under Contract No. W15QKN-14-9-1001, awarded by U.S. Department of Defense. The Government has certain rights in this invention.

FIG. 1 is a perspective view of a semiautonomous weapon mount with a weapon attached to the semiautonomous weapon mount;

FIG. 2 is a perspective view of the semiautonomous weapon mount;

FIG. 3 is a front view of the semiautonomous weapon mount;

FIG. 4 is a back view of the semiautonomous weapon mount;

FIG. 5 is a first side view of the semiautonomous weapon mount;

FIG. 6 is a second side view of the semiautonomous weapon mount;

FIG. 7 is a top view of the semiautonomous weapon mount; and,

FIG. 8 is a bottom view of the semiautonomous weapon mount.

The portions illustrated by solid lines are the portions for which the claimed design is intended. Any broken lines on the figures are for illustrative purposes only and form no part of the claimed design.

1 Claim, 8 Drawing Sheets
